SLASHER

Homer H. Grier, New Holland, Ga.

Application September 23, 1939, Serial No. 296,245

1 Claim. (Cl. 28—28)

This invention relates to a slasher and more especially to a particular arrangement of drying cylinders whereby yarn can be more efficiently and speedily treated. It is common practice in textile manufacturing to apply a coating of size solution to the warp strands so that the fibers will be consolidated thus giving added strength to the yarn. The size must be properly dried after it has been applied to the yarn so that it will not decay when wrapped into a package. This coating of dried size on the individual strands is of particular value when the yarn is woven into a fabric because the added strength and the consolidation of the fibers very often prevents the breaking of ends during a weaving operation.

It is a well known fact that many mills have installed therein what is commonly known as normal two cylinder slashers. These machines were designed for efficient work but in recent years they have often proved to be inadequate because their production is due primarily to the lack of drying surface which dries the yarn after it has passed through the size solution and before it is wound into a package. Also these slashers have been installed in the mill as close as possible to each other, or to other textile machinery, so as to conserve space in the mill. In order to prevent the respacing of the machines and at the same time to give the necessary additional drying surface, an additional detachable drying cylinder must be provided at a convenient location, which will not ordinarily interfere with the other portions of adjoining machinery.

It is therefore an object of this invention to provide an additional drying cylinder for the normal two cylinder slasher in a position above the lease rods on the slasher frame. Where the conditions warrant, it is preferable to suspend this additional cylinder from the ceiling of the room in which the slasher is located so that the supporting framework for the same will not interfere with the manipulation of the lease rods and other operations performed in this vicinity of the machine.

It is a further object of this invention to provide an additional cylinder above the lease rods of a normal two cylinder slasher which is driven solely by the frictional contact of the yarn passing thereover and whose horizontal projection is disposed within the confines of the normal slasher frame therebelow. By providing suitable anti-friction bearings for this additional cylinder, the yarn can be caused to contact substantially the entire circumference of the cylinder thus insur-

ing that the maximum drying surface will be utilized. Also by providing this additional cylinder, the conventional slashers which are now in use can be remodeled so as to be equivalent to, or better than, the latest up-to-date slashers. 5

Some of the objects of the invention having been stated, other objects will appear as the description proceeds when taken in connection with the accompanying drawings, in which—

Figure 1 is a sectional view through a room of 10 a building showing my improved slasher;

Figure 2 is a sectional view taken along the line 2—2 in Figure 1 showing the additional drying cylinder;

Figure 3 is a view similar to the right-hand 15 portion of Figure 1, but showing the added cylinder supported by the framework of the slasher instead of being suspended from the ceiling as in the preceding form.

Referring more specifically to the drawings, the 20 numeral 10 denotes the floor of a building having mounted thereon a creel frame 11 in which warp beams 12 and 14 are rotatably mounted. From these beams a sheet of warp threads 15 are drawn, said sheets being adapted to pass over 25 rollers 16 and 17 which are rotatably mounted upon size box 18. This box has a suitable size solution 19 therein in which immersion roller 20 rotates. Also the lower peripheries of rollers 21 and 22 are submerged within the solution. After 30 the yarn leaves the roller 17 it passes beneath the immersion roller 20 and over rollers 21 and 22 which apply the solution 19 to the sheet of yarn. Additional rollers 24 and 25 are mounted directly 35 above rollers 21 and 22 respectively, and these last-named rollers are adapted to squeeze the excess size which has been applied to the sheet of warp 15.

With the size applied to the warp sheet 15, it is then necessary to dry the same, and also to separate the individual ends from each other so that the yarn will be in condition for weaving or other uses. This drying process is usually accomplished by suitable drying cylinders such as designated by the reference characters 28 and 29, said cylinders being rotatably mounted in framework 30. The cylinders 28 and 29 have suitable gears 31 and 32 associated therewith, which in turn, mesh with smaller gears 33 and 34 respectively. The gears 33 and 34 likewise have beveled gears 35 50 and 36 associated therewith, which are driven by beveled gears 37 and 38, respectively. It will be noted that the beveled gear 37 is fixedly secured upon a positively driven shaft 40, whereas the beveled gear 38 is fixedly secured upon the upper 55

end of a vertically disposed shaft 41, said shaft 41 having another beveled gear 42 fixedly secured on its lower end which meshes with beveled gear 43 on positively driven shaft 40. It is therefore seen that, as the shaft 40 rotates, both of the cylinders 28 and 29 will be caused to turn in timed relation thereto.

The structure thus far described is conventional, and is well known in the textile art as being a normal two cylinder slasher. The purpose of showing and describing this much of the old structure is to more clearly disclose the utility of the added structure which constitutes the invention.

15 The sheet of warp 15, after passing through the size box 18, passes upwardly over rollers 45 and 46, and beneath roller 47, these rollers being rotatably supported by a framework 48 at points slightly removed from the upper periphery of drying cylinder 28. After leaving the roller 47, the warp 15 passes upwardly and around the cylinder 29 and then around cylinder 28, over a roller 49, under a roller 50 and then upwardly in contact with rollers 51 and 52. The last named roller 52 is supported by a U-shaped framework 53 suspended from a ceiling 54. The warp 15 then passes around a cylinder 55, which likewise is supported by a framework 53, over a roller 56 and downwardly beneath a roller 57, after which it passes in a horizontal direction over and beneath lease rods 59, 60 and 61 which serve to separate the individual ends coming from the let off beams, such as 12 and 14. The ends then pass through comb 62 which further serves to separate the ends coming from the individual beams from each other. When the ends have become properly separated, the warp sheet 15 passes over a roller 64, beneath roller 65 and over another roller 66, from whence it is wound around a take-up warp beam 67.

40 It is seen by observing Figure 1 that the added cylinder 55 is positioned directly above the lease rods 59, 60 and 61 and above the comb 62, but due to the fact that it is suspended from the ceiling 64, the operation of these lease rods and the comb is not affected. This arrangement gives the added heating surface, which is desired in modern machinery and serves to increase the production without an expensive outlay for new equipment.

45 Special attention is also called to the location of the rollers 45, 46 and 47 which serve to guide the warp sheet 15 in substantially a concentric manner about the cylinder 28 in its travel to the periphery of the cylinder 29. By keeping the sheet of yarn spaced closely to the cylinder 28, a certain amount of predrying is effected. This particular arrangement of the rollers also makes it possible to cause the warp 15 to contact substantially all of the periphery of cylinder 29. In a similar manner the location of roller 49 causes the warp to contact practically all of the periphery of the drying cylinder 28. Similarly the rollers 52 and 56 are so positioned relative to each other and to the added cylinder 55 that its entire periphery is utilized. Therefore, it is seen that this improved slasher not only makes it possible to have more heating surface on a normal two cylinder slasher at a minimum ex-

pense, but it also provides an arrangement of rollers whereby all of the drying surface will be utilized.

Attention is again called to the added cylinder 55. By referring to Figure 2 it is seen that this cylinder is rotatably mounted in uprights 75 which, in turn, are supported by the U-shaped members 53. As heretofore stated, this cylinder is mounted in anti-friction bearings such as designated by the reference characters 75a so that it will be possible to pass the yarn around the cylinder and rotate it by frictional contact. This cylinder is normally heated by steam which is caused to enter the same by means of the intake pipe 77 and which is discharged from the cylinder 15 by means of a pipe 78. From the discharge pipe the steam passes through trap members 79 and 80. At this point practically all of the steam has been condensed into a liquid.

20 Figure 3 shows a slightly modified form of the invention in which like reference characters will apply to corresponding parts which are shown in Figures 1 and 2. The chief difference in this form and that of the preceding form is the manner in which the added cylinder 55 is supported. 25 Sometimes local conditions will not warrant a suspension of the cylinder 55 from the ceiling of the building; consequently, other means must be provided. In such cases an inverted U-shaped member 81 may be mounted upon the framework 30 of the slasher and upon this U-shaped framework the uprights 75 and the added cylinder 55 are mounted. This type of mounting is desirable especially where the slasher is to be constructed in a single self-contained unit.

35 In the drawings and specification, there has been set forth a preferred embodiment of the invention and although specific terms have been employed, they are used in a generic and descriptive sense only and not for purposes of limitation, 40 the scope of the invention being set forth in the appended claim.

I claim:

45 A yarn slasher having a size box at one end and a take-up beam at the other end, three drying cylinders located at progressively increasing heights beginning near the size box and terminating near the take-up beam end of the slasher; a framework disposed above the first cylinder and having three rollers therein the yarn being 50 led above the first two of said rollers and beneath the third roller, for guiding the yarn from the size box over the first cylinder and out of contact therewith, the third roller being in close proximity to the periphery of the second cylinder 55 for depositing the yarn onto the second cylinder at a point substantially parallel with the axis of the second cylinder, and thence almost around the first cylinder, means for guiding the yarn from the first cylinder at a point almost in perpendicular alignment with the point where the yarn first contacts the second cylinder to the third cylinder, a pair of rollers in close proximity to each other and also in close proximity to the surface of the third cylinder for guiding the yarn 60 to cause it to almost encircle the third cylinder, and means for then guiding the yarn from the third cylinder to the take-up beam.

65 HOMER H. GRIER.
